UNITED STATES PATENT OFFICE.

WALTER G. TURPISCH, OF STAPLETON, NEW YORK.

DESIGN FOR A CIGARETTE-PACKAGE HOLDER.

Application filed February 8, 1926. Serial No. 16,447. Term of patent 7 years.

To all whom it may concern:

Be it known that I, WALTER G. TURPISCH, a citizen of the United States, residing at Stapleton, Staten Island, in the county of Richmond and State of New York, have invented a new, original, and ornamental Design for Cigarette-Package Holders, of which the following is a specification, reference being had to the accompanying drawing, forming part thereof.

The ornamental design for a cigarette package holder, as shown.

WALTER G. TURPISCH.
